UNITED STATES PATENT OFFICE.

WALLACE P. GROOM, OF BROOKLYN, NEW YORK.

BALING-PRESS.

SPECIFICATION forming part of Letters Patent No. 239,162, dated March 22, 1881.

Application filed October 2, 1880. (No model.)

To all whom it may concern:

Be it known that I, WALLACE P. GROOM, of the city of Brooklyn, in the county of Kings and State of New York, have invented certain new and useful Improvements in Baling-Presses and in Gearing for Driving the Same, and for other purposes, of which the following is a specification.

My invention relates to what are known as "continuous presses," in which a traverser or plunger is reciprocated in a rectangular trunk or chamber. While the plunger is back the cotton or other fibrous material to be baled is put into the trunk or press-chamber in small quantities in advance of said plunger, and when the plunger makes its forward stroke or movement any material introduced in front of it is forced forward and tightly compressed in said trunk or chamber. The compressed material is divided at proper intervals by dividing pieces or plates, which are inserted, while the machine is in operation, through the feed-opening in the trunk or press-chamber. These pieces or plates divide the compressed material into bales and supply openings needed for tying the said bales. It is desirable in presses of this kind that the forward or working stroke of the plunger should be made slowly, owing to the great pressure to be overcome, and that the backward or return stroke, in which no work is to be done, should be performed as rapidly as practicable to save time.

To this end one feature of my invention consists in a pair of intermeshing spur-wheels of equal size and form rotating in the same plane, each having its toothed periphery composed of two arcs of different radii, each arc having a number of teeth corresponding to the number of tooth-spaces of the other arc, and having at each end of the arc of greater radius a large tooth, and at each end of the arc of lesser radius a space for the reception of said large tooth. During the forward or working stroke of the plunger, which may be connected with one of the wheels by a pitman or connecting-rod, the arc of lesser radius upon the driving-wheel engages with the arc of greater radius upon the wheel to which the pitman is connected, and the movement of the plunger is slow; but on the backward or return stroke the arc of greater radius upon the driving-

wheel engages with the arc of lesser radius upon the other wheel, and the movement of the plunger is comparatively quick.

Other features of my invention consist in the combination of pairs of intermeshing spur-wheels, the wheels of each pair being of equal size and form and rotating in the same plane, and each wheel having its toothed periphery composed of two arcs of different radii, each arc having a number of teeth corresponding to the number of tooth-spaces in the other arc and other spur-wheels, whereby I produce a very desirable arrangement of gearing for baling-presses.

Another feature of my invention consists in the combination, with a press trunk or chamber and a plunger adapted to be reciprocated therein, of friction-wheels arranged in bearings outside the chamber and projecting through the same, so as to sustain the weight of the plunger and lessen the friction, and means for adjusting or setting up said wheels to cause them to project more or less into the chamber. In presses of this character it is desirable to prevent the pressed material from a return or retrogressive movement due to its elasticity when the plunger commences its backward or return stroke and the pressure thereof is removed from the pressed material. In the press shown in Letters Patent granted to me April 27, 1880, and numbered 226,998, this tendency is obviated by providing the press trunk or chamber internally with ratchet-shaped teeth, which offer a resistance to the forward movement of the material, and also prevent the retrogressive movement of such material as the plunger recedes.

The elasticity of the pressed material outward or sidewise is not always sufficient to cause it to properly engage suddenly with the first of these notches; and to obviate this difficulty, another feature consists in a press-chamber provided with such ratchet-teeth, having immediately preceding said teeth a concave recess, and having in the face of the tooth or teeth next following said recess a series of smaller ratchet-teeth. The concave recess permits the material, as it is pressed forward by the plunger, to gradually expand, and said material is then gradually contracted, so that after passing the concave recess the elasticity caused by the expansion and subsequent lat-

eral compression will cause it to expand sufficiently to engage with the first of the ratchet-teeth, and by the action of the smaller ratchet-teeth the material of each feed is separately engaged, and is also contracted by successive steps, so that upon reaching the second full-sized ratchet-tooth it will engage strongly therewith. In connection with such a press there is preferably employed a condenser adapted to be reciprocated in a box or chamber parallel with the press trunk or chamber, so as to subject the loose material to a preliminary pressing to form it into layers, and there is also employed a feeder having a movement transverse to the movement of the plunger for feeding such layers of condensed or partially-compressed material into the press trunk or chamber.

Another feature of my invention relates to mechanism for reciprocating the said condenser; and it consists in the combination, with a press-chamber, reciprocating plunger, and condenser, of racks attached to said condenser and to a stationary support, a pinion or pinions placed between and engaging with both said racks, and mechanism for reciprocating said pinions, whereby the length of movement of said movable racks is double that of the pinion or pinions, and the condenser given a long movement or stroke by a comparatively short stroke of the operating mechanism.

Another feature of my invention consists in the combination, with a press trunk or chamber, a plunger fitted thereto, a condenser, and a feeder, of a spring-lever, or a lever comprising an elastic portion for operating said feeder, whereby, in case the feeder is blocked in any way or prevented from making its full movement, breakage of the operating mechanism is prevented.

Another feature consists in the combination of a press-chamber, a reciprocating plunger, a feeder and mechanism for moving it inward, and a spring or springs for assisting the outward movement of the feeder, whereby all shocks upon the operating mechanism are in a great measure obviated.

Other features of my invention consist in the combination, with a press-chamber, a reciprocating plunger, a reciprocating condenser, and a condenser box or chamber having an opening for the introduction of material therein, of a pivoted lateral folder, which is moved into a position parallel with the movement of the condenser as the latter advances, and so presses inward all material projecting outside the feed-opening in the condenser-box. The said folder is preferably weighted, so as to be automatically opened, and is closed by an incline upon the condenser; and in order to prevent injury to the hand of an operator or to tools or implements, if caught by the folder in its movement, the latter is pivoted to supports which are capable of yielding.

Another feature of my invention consists in a novel combination, with a press, of a bell or other signal and an adjustable trip adapted

to be secured to the dividing-plates and to move therewith, for the purpose of tripping or operating the bell or signal and notifying the operator when a bale is completed and the insertion of another dividing piece or plate is required.

Another feature of my invention consists in a novel combination of devices whereby, in case of the feeder being prevented from completing its full inward movement, a clutch will be operated to disengage the driving mechanism and stop the plunger.

In the accompanying drawings, Figure 1 represents a longitudinal section through a press embodying my invention. Fig. 2 represents a partly-sectional plan thereof. Fig. 3 represents a side view of two of the driving-wheels of the press. Fig. 4 represents a horizontal section through certain of the driving-wheels. Fig. 5 represents a detail section of a small portion of the toothed interior of the press trunk or chamber upon a larger scale. Fig. 6 represents a side elevation of the press. Fig. 7 represents a horizontal section thereof upon the dotted line $x x$, Fig. 6, and upon a larger scale. Fig. 8 represents a detail of the trip, showing a method of attaching it to the dividing pieces or plates for tripping the bell or signal; and Fig. 9 is a detail view of mechanism of modified form for operating the condensers.

Similar letters of reference designate corresponding parts in all the figures.

A designates the press trunk or chamber, the sides of which are continued so as to form the side frames, A', for supporting the operating mechanism.

B designates a plunger fitted to the trunk or chamber, and adapted to be reciprocated therein by a pitman or connecting-rod, B'. This connecting-rod or pitman derives its movement from a crank-pin, a, between the wheels C C, which, in turn, are driven by other wheels, D D, an intermediate wheel, D', and a pinion, D². Upon the outer ends of the shaft D³, upon which the pinion D² is fitted, are wheels D⁴, which derive motion from pinions D⁵ upon a main driving-shaft, D⁶, provided with pulleys D⁷ and fly-wheels D⁸. This arrangement of driving mechanism, though very desirable because of its compactness and great power, may be varied in a variety of ways to suit different circumstances or the character of the material to be pressed. One particular novelty in this driving mechanism is the peculiar construction of the wheels C C and D D, which are adapted to numerous other kinds of machinery where an alternate quick and slow movement is desired. Taking, for example, one pair of intermeshing wheels, C D, I will now describe their peculiarity. The toothed periphery of each wheel is composed of two arcs which are of different radii and have the number of teeth in each arc corresponding to the number of tooth-spaces in the other arc. The two radii of each wheel may bear any relation to each other, provided

that the radii of the other wheel are the same. Each wheel is preferably provided at each end of its arc of greater radius with a large long tooth or projection, *b*, of peculiar shape, so as

5 to change the movement from quick to slower, or vice versa, gradually and without jar, and at each end of its arc of lesser radius with a notch or space, *c*, for the reception of the long tooth or projection *b* of the other wheel, so as 10 to provide for the strong engagement of the wheels when the change in motion is made twice in each rotation.

For the purpose of economizing metal and labor in construction as well as space, the wheels 15 *D* and *D'* are cast together, as shown clearly in Fig. 4, and they rotate upon a common shaft, *d*, receiving motion from the single pinion *D*².

In case the plunger should meet with any 20 obstacle great strain might be thrown upon the crank-pin and upon the wheels *C*, sufficient perhaps to bend their shafts. It will be observed, however, that at the time the plunger is making its forward or working stroke, when this is 25 most likely to occur, the wheels *C* overlap the sides of the intermediate wheel and prevent their interlocking therewith; but to render the interlocking of the wheels *C* with the intermediate wheel impossible at any point of their rotation each of the wheels *C* is provided upon 30 its outer side with a flange, *e*, which projects upon the outer side of the wheel *D*, as shown clearly in Fig. 4.

It will be observed that, inasmuch as the 35 wheels *C* and *D* are of equal size and form, when the wheels *C* are not provided with the flanges *e* the wheels *C* and *D* may be cast from the same pattern, and may be substituted one for the other without changing at all their relation to each other.

40 The pinion *D*² is locked to its shaft *D*³ by means of a clutch, *f*, and by the operation of a bell-crank lever, *f'*, may be moved to engage with the clutch or to release it therefrom to stop the plunger, for a purpose hereinafter described.

45 In order to support the plunger and lessen the friction incident to the reciprocation of the same, I employ friction-wheels *E*, which are supported in bearings outside the chamber of the press, as shown clearly in Fig. 1, and are 50 adapted to be set up by screws *g*, so as to project more or less into the chamber of the press. One of the important advantages of supporting these friction-wheels in bearings outside the press trunk or chamber is that lubricating 55 material, such as oil, may not soil the material to be pressed, such as cotton, as it would if applied to the journals of rollers or friction-wheels when supported in bearings in the plunger.

In order to prevent any backward or retrogressive movement of the material as the plunger leaves it to commence its backward or return stroke, and which might be due to the elasticity of the compressed material, I provide the press trunk or chamber *A* internally with 65 small ratchet-shaped teeth *h*, into which the pressed material springs and remains engaged as the plunger commences its backward or re-

turn stroke, and which prevent retrogressive movement of the pressed material. As the 70 pressed material approaches the exit end of the press trunk or chamber its lateral elasticity is gradually subdued, and to conform to this changing condition of the material it will be observed that the ratchet-teeth decrease in length and depth gradually from the entrance to the 75 exit end of the press trunk or chamber, the angle of their faces preferably, however, remaining the same. So far as described these ratchet-teeth form no part of this invention, but are 80 described and shown in my above-referred-to Letters Patent. Some difficulty has, however, been experienced with certain materials, owing to the fact that when pressed their side elasticity is very little, and not sufficient to cause them to engage as strongly as is desired with 85 the first of the ratchet-teeth. To obviate this I form in the interior of the press trunk or chamber, and immediately preceding the ratchet-teeth, a concave recess or cavity, *h'*, as shown more clearly in Fig. 5, which represents a section of a small part of the press trunk or chamber, and in the face of the tooth *h*² next following the concave recess or cavity I form a series of smaller teeth. (Also clearly shown in Fig. 5.) It will be understood that as the material is forced by the plunger past the concave 90 recess or cavity the pressed material has an opportunity to gradually expand to fill the deepest part of said recess or cavity, and is then as gradually contracted, so that when it passes 95 out of the recess or cavity its lateral elasticity will cause it to spring into and engage strongly with the ratchet-teeth. By the smaller ratchet-teeth in the face of the tooth *h*² the material of each feed is held against retrogressive movement until the material of successive feeds 100 equals the length of one of the full-sized ratchet-teeth.

It will be observed that the back edge of the concave recess or cavity *h'* is somewhat abrupt, and when so made any loose material that may be carried back by the plunger, and which projects beyond the edges thereof, is scraped off by said back edge.

Turning, now, to other parts of the machine, 115 *F* designates a condenser adapted to be reciprocated parallel with the movement of the press-plunger in a box or condenser-chamber, *F'*, at one side—in the present instance on top of the press-chamber. This box or chamber 120 has in its side—in this case the top side—an opening, *F*², through which material may be introduced, and by the forward movement of the condenser the loose material so introduced is condensed or partly compressed against one 125 end of the condenser box or chamber. The condenser may be moved by a bifurcated rod, *F*³, as shown in Figs. 1 and 2, attached directly to it; but the mechanism shown in Fig. 9 for moving the condenser possesses 130 some novel features, and I will now describe them.

To the condenser itself, preferably upon each side, are attached racks *i*, and beneath these

racks, to a stationary support—here formed by the condenser-box F' —I attach other racks, i , facing the racks i . Between and engaging with both racks of each pair is a pinion or pinions, j , one being here shown upon each side, and these pinions are secured in bearings in the bifurcated arm or rod F^3 , which is connected at its other end with an operating-lever, F^4 . This lever, which is pivoted at k , is preferably 10 bifurcated at its lower portion, which straddles the connecting-rod or pitman B' , and in said bifurcated portion is a curved slot, l , of very peculiar formation, which engages with and receives within it a pin, m , upon the pitman or connecting-rod B' . The form of the slot l in the lever F^4 is so regulated that the entire forward movement of the condenser F to compress the loose material will take place during the latter part of the first half of the backward stroke of the plunger, and while the plunger completes the first part of the other half of such stroke the condenser is held securely in place, and the back wall of the condenser-box F' and the end of the condenser between which is the partially-pressed or condensed layer of material form walls, between which works or moves inward a feeder, G , to force the layer of condensed material into the trunk or chamber A . The feeder G is fitted in guides n upon each side of the end of the condenser-box F' , as clearly shown in Fig. 2, and is adapted to be reciprocated therein by any suitable mechanism, that preferably being employed, however, which will move the feeder inward until the end thereof is flush with the inner wall of the trunk or chamber, and there hold it, closing the hole or opening through which the feeder works while the plunger passes it. The mechanism here represented for this purpose 40 consists of a lever, G' , pivoted to a standard, G^2 , and deriving its motion through rods G^3 from other levers, G^4 , pivoted at o to the side of the press trunk or chamber, and carrying upon their ends rollers engaging with cam-slots o' in each side of the plunger.

As represented in Fig. 2, the lever G' is composed of a rock-shaft, p , an arm, p' , extending upon one side thereof, and connected with the feeder by means of a link, p^2 , and arms p^3 , which extend upon the other side of the rock-shaft and have the rods G^3 connected to them.

As clearly shown in Fig. 1, the end of the arm p' , which is attached to the feeder G , is thin, so as to possess considerable elasticity, and in case of any obstacle to the complete movement of the feeder this elastic portion will yield and prevent breakage.

When the plunger is reversed in motion and increased in speed a considerable shock may be caused by the reversing of the feeder-operating mechanism, particularly the cam-slots o' and the studs of the friction-rollers working therein, and to obviate this difficulty I employ a spring or springs, q , under the feeder, which exert an outward pressure upon said feeder and assist in its outward movement when the same is permitted by the changed movement

of the plunger. In this instance the springs q are coiled around rods q' , which are secured at the back wall of the condenser-box F' and project upwardly through lugs q^2 at the top of the feeder G . The springs are inserted between the supports for the rods q' and said lugs q^2 ; but they might be attached in other ways, and the mechanism for working the feeder might be variously modified.

I have previously said that in the top of the condenser box or chamber F' is an opening, F^2 , through which loose material is introduced into the box or chamber, and this opening is closed 80 by a hinged or pivoted folder, H . (See more particularly Fig. 1.) This folder is pivoted in supports or bearings r , and at its rear end is a weight or weights, r' , so that when not otherwise actuated it tends toward an open position 85 relatively to the opening F^2 , as shown in Fig. 1. As the condenser moves forward this folder is moved into a position parallel with the movement of the condenser, and crowds into the proper place all loose material that may project outside the condenser, so that as the condenser moves forward under the folder all such material is compressed into a compact and well-defined layer, which may be easily pushed into the press trunk or chamber by the movement of the feeder. Any suitable means may be employed for so moving the folder, though I prefer, as here represented, to have it moved from or by the movement of the condenser itself. As will be seen in Figs. 1 and 6, the condenser is provided with inclines s , which engage rollers s' upon the folder as the condenser moves forward and moves the folder, as aforesaid.

In feeding loose material through the opening F^2 in the condenser box or chamber there is a possibility of the hand of the operator or his implements being caught under the descending folder H , and to prevent bodily injury in case of such an accident the bearings 105 or supports r , in which the folder is pivoted, are adapted to yield, they being provided with springs s^2 , (shown clearly in Fig. 6,) which permit of this.

The dividing pieces or plates I , which I have hereinbefore referred to, are shown in Figs. 6 and 7, and consist of rectangular flat pieces fitting the internal transverse section of the press-chamber A , and adapted to be fed into the same in a manner similar to that in which a layer of partly-pressed material is introduced by the feeder G . After the dividing-pieces are so inserted at regular intervals they are carried forward through the press trunk or chamber by the action of the plunger. These 115 dividing pieces or plates are formed with grooves t in each side, which afford provision for introducing a wire tie or band for tying the pressed material into separate bales, and ordinarily the closest watchfulness is required 120 on the part of the operator to insure the insertion of these dividing-pieces at the proper time. To obviate the necessity of such embarrassing watchfulness I employ a bell, J , or

a signal attached or situated at the side of the press trunk or chamber A, and to trip the bell or sound the signal at stated intervals I employ an adjustable trip, J', (see Fig. 8,) comprising two elastic fingers adapted to grasp the dividing piece or plate, as shown, and project through one of the tying-slots in the press trunk or chamber, so as to engage with the connection to the bell or signal as the 10 dividing piece or plate passes it.

In lieu of the bifurcated trip J', I may employ a piece adapted to be otherwise secured to the dividing pieces, or driven into the pressed material, if desirable.

15 In order to prevent the dividing pieces or plates from engaging with the ratchet-teeth h upon the press trunk or chamber, I provide said chamber with longitudinal plain surfaces or bearers h³ upon certain or all of the walls 20 thereof. I have previously described the pinion D² of the driving mechanism as locked fast to the shaft D³ by means of a clutch, f, and I will now describe the manner of the operation and the purpose of said clutch.

25 In case of an accident, so that the feeder should only perform a partial inward movement, and perhaps only partially insert a dividing piece or plate, I, into the press trunk or chamber, the plunger moving forward would 30 strike against said dividing piece or plate, and certainly cause a very serious break of some part of the press; and to obviate this I employ a pawl or dog, K, which is obtruded in the way of the plunger at each outward movement of the feeder and drawn out of the way of the plunger by each complete inward movement of the feeder. As clearly shown in Fig. 1, the end of the pawl or dog and the top of the projection u upon the plunger, with which

40 it may engage, are both inclined—or one only may be inclined—so that when the plunger moves backward or returns the pawl or dog will be automatically lifted out of the way. If the plunger be moving forward, however, 45 and the pawl or dog be not raised out of the way, the projection u will strike it, and, moving it forward, will, through a rod, v, operate the bell-crank lever f' and shift the pinion D² so as to disengage it from the clutch f and stop the plunger. The pawl or dog K is 50 connected to one end of a lever, w, pivoted to a standard, L, and the other end of said lever projects in the way of the lugs q² projecting from the back of the upper part of the feeder

55 G. When the feeder has nearly completed its inward movement it strikes against the said lever w and raises the pawl or dog K out of the way of the plunger; but if it does not, for any reason, complete its inward movement the 60 pawl or dog is not raised, and, being operated on by the plunger, the latter is stopped, as before stated, and the breakage of the press avoided. The mechanism through which the feeder is connected to the pawl or dog and 65 through which the pawl or dog shifts the pin-

ion might be modified in various ways, the mechanism here shown being simply one of several arrangements that suggest themselves.

By my invention I provide a very powerful press which may be easily operated, and in 70 the operation of which the liability of accidents to the operator or to the machinery is greatly lessened.

What I claim as my invention, and desire to secure by Letters Patent, is—

75 1. A pair of intermeshing spur-wheels of equal size and form, rotating in the same plane, each having its toothed periphery composed of two arcs of different radii, each arc having a number of teeth corresponding to the number of tooth-spaces in the other arc, and having at each end of the arc of greater radius a large tooth, and at each end of the arc of lesser radius a space for the reception of said large tooth, substantially as specified. 80

85 2. The combination of the pinion D², the intermeshing spur-wheel D', and the pairs of intermeshing wheels D and C, rotating in planes upon each side thereof, each of the wheels D and C having its toothed periphery composed 90 of two arcs of different radii, and each arc having a number of teeth corresponding to the number of spaces in the other arc, substantially as specified.

95 3. The combination of the intermediate spur-wheel, D', the pairs of wheels D and C, rotating in planes upon each side thereof, each of the wheels D and C having its toothed periphery composed of two arcs of different radii, and each arc having in it a number of teeth 100 corresponding to the number of spaces in the other arc, and the wheels C having upon their outer sides flanges e, which embrace the said wheels D, substantially as specified.

105 4. The combination, in a press, with a chamber, a plunger fitted thereto, and mechanism for reciprocating said plunger, of friction-wheels arranged in bearings outside said chamber and projecting into the same, and means for adjusting said wheels to cause them to project 110 more or less into said chamber, substantially as specified.

115 5. The press-chamber A, provided internally with the ratchet-teeth h and the preceding concave recess h', and having in the face of the ratchet tooth or teeth next following said recess smaller ratchet-teeth, substantially as specified.

120 6. The combination, in a press, of a press-chamber, a plunger fitted thereto, mechanism for reciprocating said plunger, a condenser, racks attached to said condenser and to a stationary support, a pinion or pinions between and engaging with both said racks, and mechanism for reciprocating said pinion or pinions, 125 substantially as specified.

130 7. The combination, in a press, of a chamber, a plunger fitted thereto, mechanism for reciprocating said plunger, a feeder for supplying material to said press-chamber, and

movable transversely thereto, and a spring-lever for moving said feeder, substantially as specified.

8. The combination, in a press, of a press-chamber, a plunger fitted thereto, mechanism for reciprocating said plunger, a feeder for supplying material to said chamber, movable transversely thereto, mechanism for moving said feeder forward toward said chamber, and a spring or springs assisting its return movement, substantially as specified.

9. The combination, in a press, with a chamber, a plunger fitted thereto, mechanism for reciprocating said plunger, and a reciprocating condenser, of a pivoted folder under which the condenser passes, and mechanism for moving said folder into a position approximately parallel with the movement of the condenser as the latter passes under it, substantially as specified.

10. The combination, in a press, with a chamber, a plunger fitted thereto, mechanism for reciprocating said plunger, and a reciprocating condenser, of a pivoted folder and an incline upon the condenser for acting upon said folder to move it into a position approximately parallel with the movement of the condenser as the latter passes under it, substantially as specified.

11. The combination of the condenser F, 30 provided with an incline, s, the pivoted folder H, the weight r', and the yielding supports or bearings r, all substantially as specified.

12. The combination, in a press, of a press-chamber, pieces or plates for dividing the 35 pressed material, a bell or signal attached to the press, and a detachable trip adapted to be secured to any of the said pieces or plates for tripping or operating the bell or signal, substantially as specified.

13. The combination, in a press, of a chamber, a plunger fitted thereto, a shaft through which motion is transmitted to said plunger, and a clutch upon said shaft, a feeder movable transversely to the said chamber, and mechanism for moving said feeder, a dog adapted to obtrude itself in the way of the plunger connected with said clutch, and connected with the feeder, so that it is moved out of the way of the plunger as the feeder moves inward, 45 substantially as and for the purpose specified.
